UNITED STATES PATENT OFFICE.

JOHN BECK, OF CARNEGIE, PENNSYLVANIA.

MINER'S CAP.

SPECIFICATION forming part of Letters Patent No. 595,595, dated December 14, 1897.

Application filed June 24, 1896. Serial No. 596,765. (No model.)

To all whom it may concern:

Be it known that I, JOHN BECK, a citizen of the United States of America, residing at Carnegie, in the county of Allegheny and State 5 of Pennsylvania, have invented certain new and useful Improvements in Miners' Caps, of which the following is a specification, reference being had therein to the accompanying drawings.

10 This invention relates to certain new and useful improvements in miners' caps, and relates more particularly to attachments for the ordinary cap that will protect the eyes of the wearer from danger of injury.

15 The invention has for its object to provide simple and efficient means for the above purpose, and, furthermore, a construction that may be readily attached to the ordinary cap and that will be extremely simple in its nature, strong, durable, effectual in its operation, and comparatively inexpensive to manufacture; furthermore, a construction wherein the shield or eye-protecting device may be readily folded within the cap when not desired by the wearer for use.

20 With the above and other objects in view the invention finally consists in the novel construction, combination, and arrangement of parts to be hereinafter more specifically 30 described, and particularly pointed out in the claims.

In describing the invention in detail reference is had to the accompanying drawings, forming a part of this specification, and 35 wherein like letters of reference indicate similar parts throughout both views, in which—

Figure 1 is a front elevation of a miner's cap, showing my attachment secured thereto. Fig. 2 is a plan view of the shield.

40 The arms *ff* protrude from a body *f'* of sheet metal, which is soldered or otherwise secured to the plate *a*.

The plan view of Fig. 2 shows the arms *ff*, and it also shows the stem engaged by the 45 arms. It shows also the hooked end of the stem entering the hole *e* of the plate *c*. In view of this illustration further views showing that construction are thought unnecessary.

50 To the inside of the cap on the underneath side of the top portion is secured a plate or

piece of metal *g*, to which is hinged a strap *h*, and to this strap *h* is hinged the frame *k* of the eye-shield, said frame carrying a netting *l*, which may be composed of fine wire or any 55 suitable material that will form a protection for the eyes.

By reason of the shield attachment being hinged on the plate *g* and at the intersection of the strap and shield-frame it will be observed that the shield can be folded back in the cap when it is not desired for use and will be entirely out of the way. When it is desired to use the same, by raising the cap at the front the shield can be pulled down in 65 position over the eyes and will be held firmly by the cap on the head.

I also desire to call attention to the various uses to which the shield may be applied outside of the case shown herewith, as it will be 70 observed that the same will be very useful for threshers to protect the grain from striking the eyes, and may be readily secured to any ordinary cap or hat and folded up in the same in the manner heretofore described when 75 not in use.

It will be observed that various changes may be made in the details of construction without departing from the general spirit of 80 my invention.

Having fully described my invention, what I claim as new, and desire to secure by Letters Patent, is—

1. In combination with a cap, a disk adapted to be secured to the crown thereof by stitching, a strap *h*, hinged to the disk, a frame *k* hinged to the strap, a netting secured to the frame, the said strap and frame being adapted to fold within the cap, substantially as described. 85

2. In combination with a cap, a disk *g*, secured to the crown thereof, a strap *h*, hinged to the disk, a frame *k* hinged to the strap and a netting *l* secured to the frame, substantially as described. 90

In testimony whereof I affix my signature in presence of two witnesses. 95

JOHN BECK.

Witnesses:

A. M. WILSON,
H. E. SEIBERT.
